UNITED STATES PATENT OFFICE.

PIETER JAN BAKKER, OF AMSTERDAM, NETHERLANDS.

APPARATUS FOR AUTOMATICALLY IGNITING FLASH-LIGHT POWDER.

Application filed October 16, 1926, Serial No. 142,124, and in the Netherlands May 5, 1926.

With the existing arrangements used for the ignition of flash-light powder, whereby the powder is ignited either electrically or by means of a firestone, the following drawbacks are experienced. In the first place it often happens that the device refuses to effectuate the ignition, and also there is considerable danger to the operator.

The present invention tries to overcome these difficulties. The same relates to a device the parts of which are arranged in such way that a proper functioning is assured under any circumstances and which will operate with perfect safety.

According to the present invention, an ignition unit, e. g. a match, is fixed in the apparatus at the appropriate place required for the ignition of the flash-light powder.

The feature of the invention resides in the following:

The lighting of this fixed match is effected by another match, mounted on a shiftable sliding-part of the device, in such way that, whilst sliding with this part, this second match is streaked along an igniting surface, lighted and after continuing its way is brought in contact with the fixed match.

Thereafter this fixed match is lighted and the flash-light-powder charge is ignited.

The second feature of this invention resides in the fact that during the igniting operation the shiftable ignition unit is successively brought in two positions prior to its being shifted along the ignition surface and whereby the first of these positions is used for fixing the ignition units in the apparatus whilst in the second position the apparatus is ready for use.

In the drawings two forms of execution of the arrangement are shown.

Fig. 1 is a top view.

Fig. 2 is a vertical section through the line 1—1 of Fig. 1.

Figs. 3 and 4 represent a longitudinal and a cross-section of another form of execution with the slide in Fig. 3 shown in partially operated position.

According to the form of execution shown in the Figs. 1 and 2, the apparatus consists of a wooden frame 1. This frame may also be made of aluminium or of any other suitable metal. Along each of the two sides of this frame a groove 2 is provided in which a portion of a slide 3 is engaged so as to guide said slide in its longitudinal movements under the influence of springs 4.

At one end of the frame 1 a small metal table 5 is mounted. This table 5 has a turning side board 6 provided with wings 7, mounted on hinges. 60

In the middle of the table 5 there is a circular opening 8 communicating at opposed points thereof with longitudinal slots 9 and 11. The slot 11 ends in a sleeve 10. In this sleeve 10 and in the slot 11, a match 12 is 65 fixed in such way that the head of this match projects into the circular opening 8 before mentioned.

Over this match the charge of flash-light powder is deposited on a sheet of paper or 70 any other suitable material.

About in the middle of the apparatus, two fixed bearings 13 are provided, on which a holder 15 can be mounted in such way, as to permit this holder to turn on the bearings 75 13 by means of two pins 14. The bottom of said holder serves as an ignition surface which is to be engaged by the movable ignition element and said holder is held in proper position to be engaged by said element by means of four small springs 80 attached to the frame 1 of the apparatus.

When appropriately fixed, this ignition surface (for which sides of any matchbox may be used) is held in a slightly sloping 85 position.

In Figure 1 the slide 3 is shown in its normal position. In this position the springs 4 are stretched, but the slide 3 is locked in said position by a spring-controlled lock 17 90 projecting into a recess provided in the side of the slide, thereby preventing the movement of said slide. By means of a rod 18 the lock 17 is connected with a lever 19 arranged alongside of the frame 1, which lever may 95 be actuated to withdraw the lock from its recess to release the slide.

In the middle of the slide 3 and on the top side thereof, a holder 20 is provided. In this holder a screw 22 is arranged in such 100 way that a match can be fixed in a vertical position for contact with the ignition surface of the holder 15.

Under the frame 1, a solid part 23 is arranged, provided with a screw head 24, by 105 means of which the apparatus can be fixed on a standard.

To the front part of this solid part 23 is fixed a bracket which is provided with two guiding blocks 26. These guiding blocks 110 have openings wherein a lock pin 27 is slideable by means of a spring 28.

This lock pin 27 carries further a stop-pin 29, transversely arranged in a hole in said lock-pin 27.

In the normal position the lock pin 27 is shifted upwards until the stop-pin 29 is resting against the upper guide block 26. When in this position, the head of the lock-pin blocks the movement of the slide 3. The lock pin 27 is attached to a Bowden-wire 28, provided with a loose handle 29'.

A metal wire 30 carrying a ring 31 is attached to the slide, for returning the same to the normal position above described.

The apparatus is operated as follows: 15 First of all the slide 3 is pulled to the normal position by means of the steelwire 30 and ring 31. In this position the slide is locked by the spring-operated lock 17.

Thereafter the match 12 is fixed in the 20 sleeve 10 of the table 5 and a sheet of paper with the charge of flash-light powder is deposited on top of the match 12.

Next, the match 21 is put in the holder 20, and fixed therein by means of the screw-pin 22, in such way that the head of said match lies about at the same height as the ignition surface arranged in the bottom of the holder 15.

If the lock 17 should accidentally be operated to release the slide 3 while the operator is still occupied with fixing the matches in the apparatus, ignition of the matches will be prevented owing to the fact that the safety lock-pin 27 is blocking the slide.

35 When the matches are fixed and the apparatus is put in readiness on the standard, the slide 3 is unlocked by pushing the lever 19. Under the influence of the springs 4 the said slide 3 is shifted until it is stopped by the safety lock-pin 27. Preferably a gong 32 is provided, operated by a hammer 33, mounted on the slide 3. This hammer 33 sounds the gong, when the above described shifting of the slide into its first operated 45 position is effected, signalling thereby that the apparatus is ready for use.

By pushing the handle 29, the wire of the Bowden-cable pulls the lock-pin 27 downwards and the slide is unlocked. Under the 50 influence of the springs 4 the slide 3 shifts in the direction of the table 5.

Whilst shifting with the slide 3, the head of the match 21 engages along the ignition surface arranged on the bottom of the holders 15 and the match is thereby ignited.

Thereafter the match 21, moves with its ignited head projecting through the slot 9 and arrives underneath the match 12 arranged in the said circular opening 8.

60 The burning match 21 lights the match 12, and thereby the charge of flash-light powder is ignited.

In order to ensure the lighting of the match 12, the movement of the slide 3 is slowed down in the neighbourhood of the

circular opening 8. This can be effected with a turning brake-pin 34 projecting in the path of the slide 3.

This brake-pin 34 is mounted on the frame 1, in such way that it may turn around a pivot 35, and is kept in position by means of two rather stiff springs 36. On its top the slide 3 is provided with an abutment 37. As the slide 3 approaches the opening 8, the abutment 37 strikes against the free end of the brake pin 34 thereby retarding the movement of the slide. The pin then turns in such way that the abutment 37 with the slide 3 may pass along.

By this arrangement the slowing down of the slide 3 is effected and thereby a certain ignition of the match 12 and the charge of flash-light-powder is obtained.

In the Figs. 3 and 4 another form of execution is shown, in longitudinal and cross-section.

In the apparatus, according to these figures, certain changes have been effected for the adaptation of same to use in the open air.

To this effect the frame 1 is formed as a closed box, one side of which can be removed by turning it on hinges, in order to enable eventual repair work to be done on the inside of the box.

The removable side of the box is kept closed by means of a hook 51 attached to same, said hook 51 cooperating with another hook 52 mounted in the frame 1.

The table 5, on which the flash-light-powder is deposited, above the notch 12 is made in one piece with the frame 1 and is accessible by means of a cover 44, turning on hinges 45.

Springs are provided, for automatically opening the cover 44, which, however, is kept closed by means of a hook 46. This hook is kept in position by the extremity of a lever 48, the other extremity of which is in the path of the slide 3.

Whilst the slide 3 is shifting under the influence of the springs 4, a projecting part 53 of the holder 15, will knock against the lever 48, shortly before the moment at which the already lighted match 21, will reach the match 12. Due to this the cover 44 is caused to open, shortly before the ignition of the flash-light powder-charge takes place.

With this form of execution the holder 15 having the ignition surface 54 is movable around a pivot 39. When ready for use, this holder is kept in position by a small spring 40, engageable in a recess of the holder 15. The ignition surface can be protected by an asbestos plate 53' arranged on the top of same.

The holder 15 is movable about its pivot 39 from a position in the interior of the frame through a slot in one wall thereof by pulling on a pin 42 projecting from said

holder and through said slot. Said slot is closed by a slide 43 which also engages said pin and when said slide is moved to uncover said slot the holder may be swung outward. 5 ly in order to renew the ignition surface 54 when this becomes necessary.

Also the construction of the locks that keep the slide in position, is somewhat changed in this form of execution. For this 10 purpose two locking-pins 27 and 17, each operated by Bowden-cables 28-28 and 38, respectively, are provided. In the normal position the locking-pin 17 engages in a recess, (not shown) in the bottom of the 15 slide and adjacent the front edge thereof.

Upon release of the locking pin 17 from its recess the slide 3 is moved forwardly until the front edge thereof is abutting the locking-pin 27 as shown in Fig. 3.

20 With this form of execution the match 21 is put loosely in the holder 20 and is kept in position by two small springs 55-56.

The pin 27 is now released from engagement with the slide and during the subsequent 25 forward movement of the slide the curved guiding surface 41 pushes the match 21 downwards and guides the head of the match on the ignition surface 54.

After the match 21 is ignited, the forward 30 movement of the slide is retarded by its engagement with a leaf spring 49, and said movement is finally stopped by contact of the slide with a projection 50. In this position the match 21 is directly beneath the 35 match 12 and ignites the same.

I claim:

1. In an apparatus for automatically igniting flashlight powder, a first ignition unit for igniting a flashlight powder, a second ignition unit for lighting said first unit, an igniting surface for said second unit, means for automatically shifting said second unit along said ignition surface in order to light said second unit, and means for moving said second unit, while burning, to a position adjacent said first unit to light the latter and thereby ignite the flashlight powder.

2. In an apparatus for automatically igniting flashlight powder in accordance with 50 claim 1, and separate locking means for retaining the shiftable ignition unit successively in two positions prior to its being shifted along the ignition surface.

3. In an apparatus for automatically igniting flashlight powder, a first ignition unit for igniting a flashlight powder, a second ignition unit for lighting said first ignition unit, a sliding member for holding said second unit, an igniting surface for said second unit, means for automatically shifting said sliding member to move said second ignition unit along said igniting surface in order to light it and for moving said second ignition unit, while burning, to a position adjacent 55 said first ignition unit to light the same,

means for locking said sliding member in a normal position required for fixing the second named ignition unit therein, means for locking said sliding member in a second position with the ignition unit carried thereby out 70 of contact with said ignition surface and prior to its being shifted along the ignition surface, said second position being reached under the influence of said shifting means after the first named locking means has been 75 actuated.

4. In an apparatus for automatically igniting flashlight powder, a first ignition unit for igniting a flashlight powder, a second ignition unit for lighting said first ignition unit, an igniting surface for said second unit, means for automatically shifting said second ignition unit along said igniting surface in order to light said second unit and for moving said second ignition unit, while burning, to a position adjacent said first unit, and means for retarding the movement of said second unit as the same approaches said first unit.

5. In an apparatus for automatically igniting flashlight powder, a first ignition unit for igniting a flashlight powder, a second ignition unit for lighting said first ignition unit, an igniting surface for said second unit, means for automatically shifting said second ignition unit along said igniting surface in order to light said second unit and for moving said second ignition unit, while burning, to a position adjacent 95 said first unit, and a spring-controlled braking element for retarding the movement of said second unit prior to the latter reaching a position contiguous to the first named unit.

6. In an apparatus for automatically igniting flashlight powder, first and second ignition units, the latter being movable and the former fixed, an ignition surface for the second unit, means for bringing the second unit successively in two positions prior to its being engaged with said ignition surface, a shiftable slide for carrying the second ignition unit, a tension spring attached to said slide for effecting the shifting motion, a lock-pin for locking said slide in the first of said two positions, and another lock-pin 105 for locking said slide in its second position.

7. In an apparatus for automatically igniting flashlight powder, a table for receiving the flashlight powder charge having an opening in the surface thereof, means for fixing an ignition unit under said table surface with the head of the ignition unit projecting into said opening, a shiftable slide carrying a second ignition unit, means for moving said slide toward the first named unit, and means igniting said second unit during said movement so that said second unit will ignite the first unit upon reaching a position adjacent the same.

8. In an apparatus for automatically ig-

niting flashlight powder, a table for receiving the flashlight powder charge having an opening in the surface thereof, means for fixing an ignition unit under said table surface with the head of the ignition unit projecting into said opening, a shifttable slide carrying a second ignition unit, means for moving said slide toward the first named unit, means igniting said second unit dur-

ing said movement so that said second unit 10 will ignite the first unit upon reaching a position adjacent the same, and means for resiliently supporting the ignition means for said second unit.

In testimony whereof I have affixed my 15 signature.

PIETER JAN BAKKER.
